[57] CLAIM

The ornamental design for a trophy base, substantially as shown and described.

DESCRIPTION

FIG. 1 is a front elevational view of a trophy base according to my design, the rear elevational view being identical;

FIG. 2 is a right side elevational view thereof, the left side elevational view being identical;

FIG. 3 is a top plan view thereof; and

FIG. 4 is a bottom plan view thereof.

FIG. 1

FIG. 2

FIG. 3

FIG. 4
